US00D845341S

(12) **United States Design Patent** (10) **Patent No.:** **US D845,341 S**
(45) **Date of Patent:** **** Apr. 9, 2019**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Jiyoon Yoon**, Seoul (KR); **Jaejeong Kim**, Seoul (KR); **Jungah Seung**, Guri-si (KR)

(73) Assignee: **SAMSUNG ELECTRONICS CO., LTD.**, Suwon-si (KR)

(**) Term: **15 Years**

(21) Appl. No.: **29/628,099**

(22) Filed: **Dec. 1, 2017**

(30) **Foreign Application Priority Data**

Aug. 25, 2017 (KR) 30-2017-0039778

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter shown in broken lines in the FIGURE illustrates a display screen or portion thereof and forms no part of the claimed design.

1 Claim, 1 Drawing Sheet
